CONNECTER

William H. Barlow, Middlebury, Conn., assignor
to Scovill Manufacturing Company, Water-
bury, Conn., a corporation of Connecticut

Application March 25, 1937, Serial No. 133,048

8 Claims. (Cl. 24—126)

The present invention relates to connectors or splicers for electrical wires, cables and the like, and has for an object to simplify and cheapen the construction of these devices and at the same time to provide a more efficient and adaptable connector or splicer for wires and cables of various sizes within the range of the device.

Another object of this invention is to provide a combined spring seat or cup and jaw coupling which may be made in one piece of sheet metal; eliminating the separate cups now used and providing means for insuring proper alinement between the spring and the jaws and proper following of the jaws when the spring cup is retracted.

15 The invention provides a sheet metal cup and cooperating jaws, so constructed as to permit the easy assembly of the jaws on the cup and to maintain the jaws in proper alinement and at the same time permit a certain amount of bodily radial action required to accommodate the jaws to wires of different sizes.

Another object is to provide an improved jaw structure which permits the jaws to be manufactured inexpensively each from a forging piece; 25 instead of having to either make the jaws by the screw machine method from rod stock and subsequent machining operations, or to make the jaws from a forging as now practiced requiring subsequent machining operations.

30 With the foregoing and other objects in view, the invention will be more fully described hereinafter, and will be more particularly pointed out in the claims appended hereto.

In the drawing, wherein like symbols refer to 35 like or corresponding parts throughout the several views.

Figure 1 is a side elevation, partly in section of a connector or splicer embodying the features of this invention, the end in section showing the 40 parts in projected position ready to receive a wire or cable, and the other end showing in dotted lines the parts in clamping position upon the end of a wire or cable.

45 Figure 2 is a longitudinal section taken through the connector axially at right-angles to the showing in Figure 1, showing at the left end the parts retracted with a wire therein ready to be clamped, and showing at the right end the parts in clamping position upon the end of a wire, the section taken on line 2—2 of Figure 1.

Figure 3 is a transverse enlarged section taken through one end portion of the connector on the line 3—3 of Figure 1, showing the jaws collapsed.

50 Figure 4 is a detail enlarged perspective view on

one of the jaws, looking at the inner side of the same.

Figure 5 is a detail enlarged perspective view 5 of the sheet metal combined spring cap and jaw retainer, and

Figure 6 is a detail sectional perspective view of the same.

Referring now to the drawing, 10 designates a 10 casing which may be of tubular form and which has its opposite end portions 11 tapered or gradually reduced to provide jaw contracting portions having reduced end openings 12 for the reception of the ends of wires, cables or the like. An expanding helical spring 13 is disposed in the intermediate portion of the casing 10 and normally 15 exerts an outward pressure toward the opposite end tapering portions 11.

At each end of the spring 13 is placed a combined spring cap and jaw retainer. This device 20 may be made of one piece of sheet metal and has a cap portion 14 having a sliding fit in the casing 10 and engaging over the adjacent end of the spring 13 to take up the end thrust thereof and hold the spring 13 in proper alinement within the casing 10. The bottom wall of the cap 14 has a 25 central projection 15 providing the jaw retainer. This projection 15 is of reduced diameter from the cap portion 14 to accommodate the inner ends of the jaws thereabout and is adapted to approach to a more or less extent into the adjacent 30 tapering end portion 11 of the casing. Each combined spring cap and retainer carries a group of jaws 16, three being shown in each group in the present instance.

The jaws 16 extend outwardly into the tapering end portion 11 of the casing and approach the end opening 12 and have beveled inner walls 17 for receiving the extremity of the wire 18 or the like as the latter is inserted through the opening 12 to retract and expand the jaws for receiving the wire 18 therebetween. The major forward portions of the jaws 16 have outer tapering sides conforming substantially to the tapering inner wall of the end portion 11 of the casing and the inner faces of the jaws 16 are transversely 40 corrugated to provide gripping surfaces 19 for engagement with the wire 18 to hold the latter firmly in the connector and make the desired electrical contact therewith when the device is used for that purpose. The rear end portions of 45 the jaws 16 have outer substantially cylindrical surfaces to lie with the confines of the cap portion 14 and are recessed at their inner sides to accommodate the retainer portion 15 therebetween.

Each jaw 16 has an inwardly and radially ex- 50

tending stud 20 at its inner end which slidably and somewhat loosely engages in an adjacent opening 21 provided in the side wall of the retainer portion 15. These studs 20 and openings 21 are so relatively disposed on the jaws 16 and retainer portion 15, respectively, that the rear or inner extremities of the jaws 16 are held in spaced relation from the spring cap 14 to admit free pivotal action of the jaws 16 on the studs 20 at all times, whether the jaws 16 are under tension of the spring 13 or the jaws 16 are retracted by pressure of the wire against the end of the retainer portion 15, as shown at the left hand end in Figure 2. Furthermore, the studs 20 permit a free radial movement of the jaws 16 about the projection 15 to accommodate the jaws to wires and the like of various sizes within the limits of the connector and also to the tapering cross-sectional area of the casing end 11. The studs 20 have a radial sliding fit in the openings 21 of the retainer portion 15, have a pivotal movement to admit the independent swinging and settling of the jaws 16 on the wire 18 and against the tapering casing end 11, and also are permitted ample 25 rocking or canting movement to permit the necessary freedom of the jaws 16 to move in all directions. The studs 20 also insure that the jaws 16 remain coupled to the spring cap 14 in all adjustments of the jaws, and the combined spring 30 cap 14 and jaw retainer projection 15 and the jaws 16 with their studs 20 are so relatively proportioned to the casing 10 that the jaws 16 are held from separation from the retainer projection 15 while the parts are assembled in the casing 35 10.

The casing 10 has a longitudinal slot 22 near each end substantially registering with the combined spring cap and jaw retainer so that a suitable implement may be introduced through the 40 slot 22 between the cap portion 14 and the inner ends of the jaws 16 for retracting the combined member 14, 15 against the tension of the spring 13 to loosen the jaws 16 from the end of the wire 18 when it is desired to free the same.

The sheet metal cap 14 with its projection 15 admits of ease in assembling the parts of the connector and keeps the jaws 16 in proper alignment, yet allows all necessary radial, pivotal and rocking movements of the jaws 16 to accommodate them 50 to different size wires or the like.

This construction also permits the jaws 16 each to be manufactured inexpensively from a single forging piece without subsequent machining operations, the stud 20 being forged with the jaw 16 55 as a part thereof.

As shown in Figure 1, at the left hand end thereof, when the connector is not in use the jaws 16 are projected outwardly by the spring 13 into the tapering end 11 of the casing until the jaws 16 are collapsed into contact with one another. The jaws 16 are held in this projected position by the spring 13 acting through the combined spring cap 14 and its jaw retainer projection 15, it being noted that the inner ends of the jaws 16 are held from contact with the cap 14 by the radial studs 20. The jaws 16 are permitted free swinging, tilting and radial movements in settling into the tapering end 11 of the casing and against one another. The outer end bevel faces 17 of the 70 jaws 16 are located adjacent the opening 12 and are adapted to receive the extremity of a wire or cable which may be forced through the opening 12. The introduction of the wire 18 first retracts the jaws 16 against the tension of the spring 13 75 until the jaws 16 are retracted sufficiently into the

tapering casing end 11 to permit the jaws to be cammed apart by their bevel edges 17. At this time the wire 18 may slide backwardly between the jaws 16 until the extremity of the wire 18 engages the end of the retainer projection 15, as shown at 5 the left hand end of Figure 2.

By forcing the wire 18 a short distance farther into the connector the combined spring cap 14 and jaw retainer 15 is retracted against the tension of the spring 13 and the jaws 16 are freed 10 or loosened from the tapering wall of the casing end 11 and may settle into proper positions about the end of the wire 18. With the jaws 16 in position about the wire 18, the pressure on the wire may now be relaxed and the spring 13 permitted to expand and move the combined cap 14 and retainer 15 outwardly to force the jaws 16 toward the tapering end of the casing portion 11 with the result that the jaws 16 are contracted upon the wire 18 and bind the gripping surfaces 20 19 thereon to firmly hold the wire 18 in the connector and with a gripping and wedging action proportionate to the outward pull on the wire 18, as shown in the right hand ends of Figures 1 and 2.

To release the wire or cable 18 from the connector, a suitable implement is introduced through the adjacent slot 22, and into the space between the inner ends of the jaws 16 and the spring cap 14, and pressed against the cap 14 to retract the same against the tension of the spring 13. This 30 operation withdraws the jaws 16 within the tapering casing end 11 and releases the pressure of the jaws 16 from the wire 18. Holding the jaws 16 thus retracted, the wire 18 may be easily pulled out of the connector.

The jaw retainer projection 15 may be pressed from the bottom of the spring cap portion 14 and the radial openings 21 be punched therein, so that the combined cap and retainer may be inexpensively manufactured from sheet metal and 40 the projection 15 be of sufficiently reduced diameter to fit between the inner ends of the jaws 16 and provide an annular cup bottom of sufficient width to cover the end of the spring 13.

The recesses in the rear ends of the jaws 16 45 are of sufficient length to leave a space 18 at the outer end of the jaw retainer projection 15 for the extremity of the wire or cable 18 so that, should the extremity of the wire or cable become misshapen or unravelled, the distorted or frayed 50 end of the wire or cable will not engage the gripping surfaces 19 of the jaws and prevent the uniform and even gripping of the jaws 16 on the wire or cable throughout the entire length of the gripping surfaces 19.

What is claimed is:

1. A connector for wires, cables and the like, comprising a casing having a tapering open end, an expanding spring in the casing, cooperating jaws disposed in the tapering end of the casing 60 and having studs at their inner ends extending radially inward, and a combined spring seat and jaw connector having a cup portion receiving the end of the spring and having a radially apertured hollow projection from the bottom of the 65 cup receiving the radial jaw studs to connect the jaws to the cup portion and hold the jaws in relative longitudinal alignment for radial and pivotal and rocking adjustments when shifted in the tapering end of the casing to receive and clamp upon 70 the end portion of a wire.

2. In a wire connector, the combination of a casing having a tapering open end to receive a wire, a group of jaws slidably disposed in the tapering end of the casing to receive the wire there- 75

between and having inwardly directed studs on their inner ends, an expanding spring in the casing, and a sheet metal cap fitting over the end of the spring to provide a seat therefor and having 5 a reduced cylindrical projection pressed outwardly from the bottom of the cap and engaging between the inner ends of the jaws and having radial openings in the side walls of the projection receiving said jaw studs to connect the jaws to 10 the cap with free pivoting and tilting and radial movements of the jaws relative to the cap and to one another during the gripping of the jaws on the wire.

3. A wire connector comprising a tubular casing having an open tapering end, an expanding 15 spring in the casing, a cap fitted to the end of the spring and having a central straight sided bottom projection with radial openings therein, and a group of jaws in the tapering end of the casing, 20 said jaws having recessed inner rear portions receiving said projection of the cap and having round studs pivotally and tiltably and slidably engaging in the radial openings of the projection to retain the jaws in relative alignment and to the 25 cap at all times.

4. A combined spring cap and jaw assembly for connectors of the type having a tubular casing with a tapering open end and an expanding spring in the casing, comprising a group of forged jaws 30 adapted to be positioned in the tapering end of the casing and having recessed inner walls at their rear ends and inwardly extending studs forged thereon in the recesses, and a sheet metal cap adapted to engage over the adjacent end of the 35 spring and having an axially disposed bottom projection of reduced diameter to engage in the recessed ends of the jaws, the outer surface of said projection being disposed in parallel relation to the axis of said casing, said projection having radial openings for the reception of the jaw studs 40 to hold the same assembled on the cap and in relative alignment in the tapering end of the casing.

5. A connector for wires and the like, comprising a tubular casing having a tapering open 45 end and a longitudinal slot adjacent said tapered portion, a plurality of jaws disposed in said tapering end provided with reduced arcuate inner end portions, an inwardly projecting pin carried by the reduced inner end of each jaw, a sheet metal 50 cylindrical cap slidable in said casing, a reduced hollow extension integral with said cap engaging within said reduced inner end portions of said jaws, said extension having openings to receive said pins, said openings being so disposed as to 55 position the inner end portions in outwardly spaced relation to the adjacent end of said cap, and an expanding spring having an end thereof engaging within said cap, said jaws when in clamping position being so positioned relative to

said slot that a releasing tool may be inserted through said slot and positioned in the space between said cap and the inner ends of said jaws.

6. A connector for wires and the like comprising a tubular casing having an open end, a plurality of clamping jaws in said casing and movable longitudinally thereof, means carried by said body engageable with said jaws to move said jaws to clamping position upon outward movement of 10 said jaws, said jaws having reduced transversely curved inner ends, an expanding spring in said body constantly urging said jaws to clamping position, a sheet metal cap interposed between said spring and said jaws, said cap having a cylindrical outer portion slidably engaging said casing 15 and a cylindrical axial projection engaging within said reduced jaw ends, said projection having a plurality of circumferentially spaced apart openings, and radial studs carried by the reduced ends of said jaws loosely engaging in said openings. 20

7. A connector for wires and the like comprising a hollow body open at one end, a plurality of clamping jaws in said body and movable longitudinally thereof, means carried by said body engageable with said jaws to move said jaws to 25 clamping position upon outward movement of said jaws, said jaws having reduced inner end portions, an expanding spring in said body constantly urging said jaws to clamping position, a member interposed between said spring and said 30 jaws, said member having a cylindrical surface slidably engaging said body, an axial projection integral with said member overlapping the reduced end portions of said jaws, said projection having radial holes therein, and pins carried by 35 said reduced end portions of said jaws engaging in said holes, said pins connecting said jaws to said member for swinging movement relative thereto.

8. A wire connector, comprising a tubular casing having a tapering end portion to receive a wire 40 therein, a group of jaws slidably disposed in the tapering end portion of the casing and having inner beveled faces at their outer ends adapted to receive the extremity of the wire thereagainst for retracting and expanding the jaws, said jaws having inwardly extending radial studs at their inner ends, an expanding spring mounted in the casing, a cap seated over the adjacent end of the spring and having a jaw coupling portion projecting between the inner ends of the jaws and 45 having radial openings therein for the reception of said jaw studs to couple the jaws to the spring cap for longitudinal movement therewith, space the jaws equidistantly about the coupling portion and to admit independent pivotal and radial tilting movements of the jaws in settling about the wire and against the inner wall of the tapering 50 end portion of the casing. 55
